COMBINED DISPLAY RACK AND CABINET FOR KEYS

Nathan S. Lieptz, Beachwood, Ohio, assignor, by mesne assignments, to Curtis Noll Corporation, Cleveland, Ohio, a corporation of Ohio

Filed Feb. 13, 1963, Ser. No. 73,547

Term of patent 14 years

(Cl. D80—9)

FIG. 1 is a front elevational view of a combined display rack and cabinet for keys embodying my new design, the rear being essentially the same as the front shown;

FIG. 2 is an elevational view taken from one side thereof, the opposite side being substantially the same as the side shown;

FIG. 3 is a front elevational view thereof, the sides being in an open position;

FIG. 4 is an elevational view taken from one side of FIG. 3; and

FIG. 5 is a reduced scale top plan view of FIG. 3.

The support pole is broken away in FIGS. 1 through 4 to indicate that said pole may be of an indeterminate length.

I claim:

The ornamental design for a combined display rack and cabinet for keys, substantially as shown and described.
